UNITED STATES PATENT OFFICE.

JOHN O. NEIKIRK, OF LOMBARD, ILLINOIS, ASSIGNOR TO RODGER BALLAST CAR COMPANY, OF CHICAGO, ILLINOIS, A CORPORATION OF MAINE.

DUMP CAR.

Application filed August 5, 1925. Serial No. 48,213.

The present invention relates to dump cars, more particularly the present invention relates to railroad cars of the dumping type and will be described with particular reference to selective dump cars, that is, cars which are so designed as to selectively deposit lading between the tracks or outside of the tracks upon which the car is mounted.

An object of the present invention is to provide an improved control mechanism for the dump doors of railway dump cars.

A further object is to provide dumping mechanism of improved sturdiness.

A further object is to provide control mechanism for railway dump cars so designed that both assembly and operation are simplified.

A further object is to provide a detent mechanism having a unitary mounting for controlling the opening movement of the dumping mechanism of railway dump cars, which detent mechanism is applicable to said dumping mechanism throughout an extended region, whereby said detent mechanism may be conveniently located.

Further objects will appear as the description proceeds.

The present invention constitutes an improvement over applicant's prior Patents No. 1,374,516, granted April 12, 1921, and No. 1,428,659, granted September 12, 1922.

Referring to the drawings—

Figure 1 is a fragmentary view in side elevation of a railway dump car embodying the principles of the present invention;

Figure 2 is a sectional view taken along the plane indicated by the arrows 2—2 of Figure 1;

Figure 3 is a sectional fragmentary view taken along the plane indicated by the arrows 3—3 of Figure 1;

Figure 4 is a fragmentary sectional view taken along the plane indicated by the arrows 4—4 of Figure 1;

Figure 5 is a fragmentary view on an enlarged scale of the structure shown in Figure 1;

Figure 6 is a view of the structure shown in Figure 5, said view being taken in the direction of the arrow 6 of Figure 5; and

Figure 7 is a sectional view taken along the plane indicated by the arrows 7—7 of Figure 6.

The numeral 10 indicates a railway dump

car mounted upon trucks, which trucks are indicated by the wheels 11—11 thereof. 55 Located between the trucks is certain dumping mechanism indicated as a whole by the numeral 12. The body of the car is provided with the side walls 13—13, which may be stiffened by means of the stakes 14—14. At 60 the ends of the car are sloping floors 15 adapted to direct lading to the dumping mechanism 12.

Mounted longitudinally of the car is the center sill structure indicated as a whole by 65 the numeral 16. Said center sill structure is provided with the cope 17 adapted to shed lading to the two sides of said center sill structure. Said center sill structure 16 is also provided with the outwardly sloping 70 bottom walls 18—18, which form part of the walls of the two hoppers 19—19 into which the car is divided by the center sill structure 16. Disposed adjacent to the side walls 13—13 are the inwardly sloping walls 20—20. 75

The space between each outwardly sloping wall 18 and the corresponding inwardly sloping wall 20 of each hopper 19 is closed by a door 21. Said doors 21—21 are swingingly mounted upon the shafts 22—22 extending 80 longitudinally of the car, which shafts 22—22 are supported by certain brackets, which will be referred to hereinafter. Said doors 21—21 are composite structures and extend to regions inwardly of the lower extremities of the sloping walls 18—18. Said doors 21—21 are controlled in their swinging movement

about the axes of shafts 22—22 by certain link mechanism indicated as a whole by the numeral 23. Said link mechanism 23 is controlled by the rotatable shaft 24, which may be rotated by any preferred means (not illustrated). Rotation of the shaft 24 in one

direction will result in an opening movement of the doors 21—21 swinging about the axes of the shafts 22—22. Rotation of the shaft 24 in the opposite direction will result in the closing movement of said doors 21—21. The doors 21—21 are provided with intermediate doors 25, which are swingingly mounted upon the longitudinally disposed shafts 26—26, which shafts 26—26 lie in proximity to the lower extremities of the outwardly sloping floors 18—18. Swinging of the intermediate doors 25 is controlled by the longitudinally 95

disposed shafts 27—27, chains or other flex-

100

105

ible connectors 28 being provided, which connectors 28 are secured to the swinging edges of said intermediate doors 25—25 and said shafts 27—27. The shafts 27—27 may be of any suitable cross section, a hexagonal conformation being shown in the present exemplification of the present invention. The shafts 27—27 are supported in brackets 29 which are located adjacent to the longitudinal 10 extremities of the dumping mechanism 12. Brackets 30 are also provided for supporting the shafts 27—27 intermediate of their lengths. The brackets 29 and 30 may be castings and are riveted or otherwise secured to 15 the under frame of the car, including the cross tie 30'. Said brackets preferably serve not only as supporting means for the shafts 27—27, but provide bearings for the shafts 22—22 which pivotally support the swinging 20 doors 21—21. Said brackets serve also as strengthening means for the sloping walls 20 and the sides of the car, being riveted or otherwise secured to said sloping walls 20—20, side walls 13—13 and stakes 14—14 as indicated by the numeral 30''. When non-round 25 shafts 27—27 are used, in order that they may have proper bearing in the brackets 29 and 30, bushings will preferably be provided having circular peripheries for rotation in 30 circumferential seats within the brackets 29 and 30. Bushings suitable for the purpose are indicated by the numeral 31 in Figure 3. The intermediate brackets 30—30 will preferably have slotted apertures 32—32, the 35 longer axes of said apertures 32—32 being vertically arranged. By reason of the slotted construction of the brackets 30—30 the matter of assembly is greatly facilitated, inasmuch as it will frequently be found that the 40 shafts 27—27 are not perfectly straight. As will be noted from an inspection of Figure 2, the extremities of the cross tie 30' are cut away on the under side to allow space for the shafts 27 and the bushings 31. The cross 45 tie 30' will ordinarily take the form of a flanged beam having a web. In order to strengthen the cross tie 30' at the extremities thereof, the brackets 30—30 are provided with upstanding flanges 33—33, which are secured 50 to the web of the cross tie 30'. Chain guides 34—34 are secured upon the shafts 27—27 for insuring smooth operation of said chains.

In order to move the intermediate doors 25—25 from their open positions toward closing position, ratchet mechanism is provided for operating the shafts 27—27, which ratchet mechanism is indicated by the numeral 35. Said ratchet mechanism does not constitute the present invention and need not be described in detail herein. It will be sufficient to state that each of the ratchet mechanisms includes a ratchet pinion 36 secured to the corresponding shaft 27. A lever 37 is provided having an operating dog 38. Oscillating 60 movement of the lever 37 will cause the dog 65

38 to engage the ratchet pinion 36 to communicate rotary motion to the corresponding shaft 27. When the ratchet mechanism 35 is not being used, the lever arm 37 is held in inoperative position within a bracket 39, a locking member 40 being provided for this purpose. When the ratchet mechanism 35 is inoperative, said ratchet mechanism will not interfere with the opening of the intermediate doors 25—25.

In order to control the opening movement of the intermediate doors 25—25, certain detent ratchet mechanism is provided, which detent ratchet mechanism is indicated by the numeral 41. One of said detent mechanisms is provided for each side of the car, and a description of one will suffice for a description of both. Each detent ratchet mechanism 41 includes a detent wheel 42, which wheel 42 is non-rotatably mounted upon its corresponding shaft 27. Bushings 43—43 are provided, having axial apertures conforming to the cross sectional contour of the shaft 27 and having circular peripheries. The peripheries of said bushings 43—43 have bearings within similar apertures in the bracket or yoke 44, which is riveted or otherwise secured to the under frame of the car. This bracket comprises two substantially parallel legs 44' and an attaching member 44'' from which these legs extend. The detent wheel 42 with the bushings, which may be used with a non-round shaft, as in the present disclosure, is mounted between the legs 44' while the dog 45 is pivotally mounted upon the member 44''. By this construction, the parts are held in proper operative relation regardless of the location of the detent mechanism upon the shaft, independent of any fixed part of the car or other means for holding them in this relation. The present construction thus differs materially from those shown in applicant's prior patents hereinbefore referred to.

The dog 45 is provided with the axial aperture 46 for the reception of a bar by means of which an oscillating movement may be communicated to the dog 45. The dog 45 lies within the overall dimensions of the car, so that it presents no projecting parts.

Each detent wheel 42 includes a pair of side walls 47—47, which side walls are provided with the teeth 48—48 located in staggered relationship about the periphery of said wheels 42. Each of the teeth 48—48 is provided with a face 49 lying in a plane approximately parallel to the axis of the shaft 27. The opposite faces, bearing the numerals 50—50, are inclined relative to the axis of the shaft 27.

In order to insure the engagement of the teeth 48—48 with the extremity of the dog 45, each of said teeth 48 is preferably of such a dimension that it extends beyond the medial plane of the detent wheel 42, that is to say,—referring to Figure 7, the teeth 48 should all

extend beyond the medial plane indicated by the numeral 51. By this construction it is impossible that a free circumferential channel could be provided for the extremity of the dog 45. The construction referred to makes it certain that the dog 45 will properly control the movement of the intermediate doors 25—25. When it is desired to allow said doors to open, the dog 45 will be oscillated, a bar (not shown) being used to apply the necessary leverage. Oscillations of the dog 45 will move said dog out of obstructing relationship with each tooth 48 in succession, but will leave it in obstructing relationship 15 with the next succeeding tooth 48. Continued oscillation of the dog 45 will therefore result in the step-by-step opening of the intermediate doors 25—25. The teeth 48—48 are so disposed that when the detent wheel is being 20 rotated by the ratchet mechanism 35, (i. e., in the closing movement of the corresponding door 25), the beveled faces 50—50 of the teeth 48—48 will engage the end of the oscillating dog 45. Inasmuch as the teeth 48—48 are in 25 staggered relationship with one another, each succeeding tooth 48 (in the closing movement of the corresponding door 25) will move the end of the dog 45 to one side or the other, whereby said detent wheel 42 and consequently the shaft 27 may be rotated. Reverse 30 movement of each detent wheel 42 will be stopped, however, by reason of the engagement between the dog 45 and the faces 49—49 of the teeth 48—48, which faces 49—49 are in 35 approximately parallel relationship with the axis of the shaft 27.

The fact should be noted that the bracket 44 provides a unitary mounting for the dog 45 and the detent wheel 42, so that the danger 40 of said dog and detent wheel getting out of proper relationship with each other is minimized. Moreover, this proper relationship is maintained regardless of the position of the bracket 44 axially of the shaft 27. It will be 45 noted that the bracket 44 may be located at any point within substantially the whole length of shaft 27, permitting a wide field of selection as to the location of said bracket 44.

The present invention provides a sturdy 50 structure which reduces the amount of keying to a minimum, which is simple to assemble and to operate, and which promotes safety.

Though a preferred embodiment of the 55 present invention has been described in detail, it will be clear that many modifications will occur to those skilled in the art. It is intended to cover all such modifications that fall within the appended claims.

What is claimed is:

60 1. In a dump car, a swinging door, a shaft for operating said door, detent mechanism upon said shaft for controlling the opening movement of said door, said detent mechanism comprising a wheel having opposed

detent teeth arranged in staggered relationship, and a dog positioned to abut said teeth in succession, said teeth extending across the medial plane of said wheel, whereby to insure that said dog will engage with said teeth in succession during the opening movement 65 of said door.

2. In a railway dump car, in combination, a sloping bottom wall forming part of a hopper, a dump door for controlling said hopper, a shaft extending longitudinally of said car for controlling said door, a bracket providing a bearing for said shaft, and a cross tie, said cross tie having a portion of its extremity cut away to provide space for said shaft, said bracket having a portion secured 75 to the web of said cross tie and providing supporting means between said cross tie and said sloping wall.

3. In a railway dump car, in combination, a dump door, a shaft for controlling the opening movement of said door under load, a detent wheel non-rotatably mounted upon said shaft, and a yoke member secured to said car and embracing said detent wheel.

4. In a railway dump car, in combination, 85 a dump door, a shaft for controlling the opening movement of said dump door, a detent wheel upon said shaft having oppositely presented detent teeth arranged in staggered circumferential relationship with one another, 90 a swinging dog adapted to be oscillated by said teeth when said wheel is rotated in one direction and adapted to stop the movement of said wheel when said wheel tends to move in the opposite direction, said teeth extending 95 across the medial plane of said wheel to insure that said dog will engage said teeth in succession during the opening movement of 100 said door.

5. In a railway dump car, in combination, 105 a dump door, a shaft for controlling the opening movement of said dump door, a detent wheel slidably but non-rotatably mounted upon said shaft, said detent wheel having 110 detent teeth arranged in staggered circumferential relationship with one another, said teeth extending across the medial plane of said wheel, and a swinging dog adapted to abut said teeth in succession in the opening movement of said door and adapted to be oscillated by said teeth in the closing movement 115 of said door.

6. In a dump car, a swinging door, a shaft for operating the said door, connections between said shaft and door, a bracket having 120 substantially parallel legs mounted upon said shaft, and detent mechanism upon said shaft between said bracket legs.

7. In a dump car, a swinging door, a shaft for operating the said door, connections between said shaft and door, a bracket having 125 substantially parallel legs mounted upon said shaft, detent mechanism upon said shaft be-

tween said bracket legs, said bracket also comprising an attached member for securing the bracket to a fixed part of the car.

8. In a dump car, a swinging door, a shaft for operating said door, connections between said shaft and door, a bracket having substantially parallel legs mounted upon said shaft, a detent wheel between said parallel

legs, said bracket comprising also an attached member for securing said bracket to a fixed part of the car, and a swinging dog mounted upon said attaching member for engaging the said detent wheel. 10

Signed at Chicago, Illinois, this 30th day of July, 1925.

JOHN O. NEIKIRK.
